FRED H. KROGER, OF RIDGEWOOD, NEW JERSEY, ASSIGNOR TO RADIO CORPORATION OF AMERICA, A CORPORATION OF DELAWARE

TRANSMISSION SYSTEM

Application filed March 19, 1930. Serial No. 437,005.

This invention relates to radio apparatus and in particular to radio transmitters including oscillation generators and radiating systems.

More in detail this invention relates to transmission lines, and to a novel method of and apparatus for connecting the output or tank circuit of an oscillation generator or amplifier through a transmission line to the circuit to be energized thereby.

In radio transmission apparatus known heretofore the transmission line is terminated at the output of the oscillation generator in a secondary winding of a transformer the primary winding of which is connected in some manner to the anode cathode circuit of the oscillation generator or to the amplifier stage fed by the generator, while the remote end of the transmission line terminates in the primary winding of a transformer the secondary of which is connected in some manner in the load circuit.

Use of the apparatus known heretofore is attended with numerous disadvantages a few of which will be listed here.

When transformers are utilized to connect the ends of the transmission line to the oscillation generator output and to the antenna radiating system considerable capacity is present between the windings of the transformers due to the size of the windings and the close spacing thereof. This inherent capacity is undesirable in all cases and especially undesirable where the apparatus is to be used to generate, transmit and utilize oscillations at the high frequencies necessary in short wave work.

Another disadvantage inherently present in apparatus of the above nature due in part from the inherent capacity between the windings and in part from the size of the windings and the apparatus is that the lines and apparatus is unbalanced with respect to ground. The latter defect results in losses in energy to ground thus directly reducing the efficiency of the transmission apparatus.

Another objection to the use of transmission lines terminating in transformers as described above results from the fact that the 50 transformers are more or less of permanent

nature and must be changed when the frequency is changed or if they are tapped the dead ends of the windings thereof not in use when higher frequencies are used are a source of losses of energy and result in change of 55 the tune of the load circuit when in operation.

The above disadvantages are obviated in accordance with the present invention by providing an auto-transformer in the output circuit of the oscillation generator or final amplifier stage. The transmission line is tapped to appropriate points on this oscillation circuit in such a manner that when the frequency is changed there are no dead ends to the 60 winding. The transmission line terminates in a second auto-transformer connected in a novel manner to the load circuit.

In one modification preferably to be used when a single tube is utilized in the final 70 stage of the oscillation generator or amplifier fed thereby the coupling between the tank circuit and transmission line includes an auto-transformer winding tuned by a capacity and connected on the one hand 75 through a condenser to the anode of the thermionic oscillation generator or amplifier and on the other hand through a tapped point to the filament of the thermionic tube. The transmission line is tapped to this inductance 80 on the one hand and on the other hand to an inductance forming a portion of the aerial circuit in such a manner as to balance the line with respect to ground and with respect to the apparatus at each end and to cause all 85 of the antenna current to flow through the coupling inductance at both ends of the transmission line.

A second modification is to be used preferably with transmitters the final stage of 90 which includes a pair of thermionic tubes in push-pull relation. This modification except for the fact that push-pull arrangement is used is similar in many respects to the modification briefly described above and 95 especially as to the manner in which the transmission line is coupled to the output of the final stage but differs in that at the remote end of the transmission line a condenser is connected in series with the inductance in 100

the load circuit to which the transmission line is tapped in such a manner as to insure that all of the current passes through all of the load inductance included between the transmission line taps and further to prevent the reactance present in an arrangement similar to the first discussed modification.

Other objects of the invention and further advantages to be obtained by the use of the 10 present novel method and arrangement of connecting the transmitter to a load circuit will be come apparent from the following detailed description and therefrom when read in connection with the drawing throughout 15 which like reference numerals indicate like parts and in which,

Figure 1 shows our novel method of connecting the transmission line between a thermionic generator having a single tube in the 20 output circuit thereof and a load circuit; while,

Figure 2 shows the method of connecting the transmission line between a thermionic generator having a pair of tubes in push-pull 25 relation and the load circuit.

Referring to the drawing, Figure 1 shows a thermionic oscillation generator or amplifier 1 having an anode 2 connected through a condenser 3 to a tank circuit 4 including an inductance 5 and parallel tuning condenser 6. The anode cathode alternating current circuit is completed through an adjustable tap 7 to the cathode 8 and of generator 1. Direct current potential is applied to the anode 30 through a choke coil 10 from a source 11 having its negative terminal connected to the cathode 8. A circuit not shown is connected at 12 between the control grid and cathode of generator 1. This circuit may be an input circuit associated with a source of varying potential or may be an oscillatory circuit coupled to the anode cathode circuit in a manner to insure oscillation of the apparatus including the tube 1. Heating current for the cathode 45 8 is supplied from a source not shown.

The transmission line 13 includes a pair of lines tapped at 14 and 15 to points on the inductance 5. The transmission lines 14 and 15 are at the remote terminal tapped at 50 16 and 17 to an inductance 18 in the load circuit which for purposes of illustration has been shown as an aerial system. A second inductance 19 is connected on the one hand through a tap 20 to the aerial and on the 55 other hand to ground G.

In operation when it is desired to change the wave length of the signals generated and transmitted all that is necessary is to tune the tank circuit 4 to the desired frequency 60 and then adjust the taps 14 and 15 along the inductance 5 to pick off the most effective voltage to be transmitted by line 13 to the aerial inductance 18. The taps 16 and 17 are now moved along the aerial inductance 65 14 to include that amount of inductance which

gives the most desirable results. The aerial may be further tuned by varying the tap 20 on the inductance 19.

By causing the current in the tank circuit 4 to flow through all of the inductance across which the transmission line is connected the transmitter output circuit and apparatus will be balanced with respect to ground as will be the transmission line connected to the output circuit.

The arrangement at the aerial end of the transmission line is such that the transmission line is completely balanced with respect to ground and at the same time the full antenna current is not required to flow through the antenna coupling inductance. At the load end of the transmission line the inductance included in the current path is considerably greater than the inductance in the antenna circuit to ground. This allows of tuning of the aerial to some extent without changing the coupling between the inductances and also allows of changing the coupling to vary the amplitude of energy transferred from the line to the aerial without varying the tune of the aerial circuit.

In the modification shown in Figure 2 the method of connection at the transmitter end is similar to that shown in Figure 1 except that in Figure 2 the final stage of the oscillation generator includes a pair of thermionic tubes 1 and 1' having their anodes 2 and 2' connected through a tank circuit 4. The variable tap 7 is connected between a point on the inductance 5 of the tank circuit and ground as in Figure 1. The transmission line 13 is tapped to the desired points on the inductance 5 at the output end and to the desired points on the inductance 18 at the antenna end of the transmission line.

In operation this modification is somewhat similar to the modification shown in Figure 1. However, in this modification the push-pull amplifier is in itself balanced with respect to ground while the transmission line tapped to the inductance 5 is balanced with respect to ground due to the fact that as in Figure 1 all of the current flowing in the transmission line flows in the inductance 5 in the output of the push-pull stage. This modification, however, differs from the modification shown in Figure 1 in that at the aerial circuit end of the transmission line a condenser 21 is connected in series with the inductance 18. This condenser causes the current to flow through all of the inductance tapped by the transmission line thereby eliminating any reactance which would be present in an arrangement as shown in Figure 1.

In both modifications at the load end of the transmission line I have provided two current paths in such a manner that the current path included in the transmission line and the transmission line can be made symmetrical and therefore the transmission line

with respect to ground is likewise symmetrical, and the line is balanced with respect to ground.

In both modifications as will be readily seen by inspection of the drawing, the power fed from the transmission line to the aerial radiating system can be varied without upsetting the antenna circuit adjustments only slight retuning being required. This characteristic also results directly in a further advantage in that the frequency transmitted may be readily shifted through a frequency range without changing the coupling inductances at either end of the transmission line and without unbalancing the transmission line or resulting in losses therein. Both modifications likewise obviate the necessity of transformers and the disadvantages resultant from the use thereof at both ends of the transmission line.

I claim:

1. A thermionic transmitter including a thermionic amplifier having a tank circuit including a tuned inductance connected through a condenser to the anode and through a point tapped on said inductance to the cathode, an aerial circuit including a pair of parallel inductances one of which is variably connected between the aerial capacity and ground and a transmission line tapped on the one hand to the inductance in said anode cathode circuit and on the other hand to one of said parallel inductances in said aerial circuit.

2. A thermionic amplifier including a pair of thermionic tubes having anodes connected through a tank circuit including a tuned inductance, a connection between the midpoint of said inductance and the cathodes of said tubes, an antenna system including a capacity connected through parallel inductances to ground, a capacity in series with one of said inductances and a transmission line tapped at one end to the inductance in said output circuit and at the other end to one of said parallel inductances.

3. In transmitting apparatus a thermionic generator, an aerial system, and means whereby the amplitude of the energy supplied to said aerial system may be varied without varying the frequency of the oscillations radiated including an aerial capacity connected through parallel inductances to ground, an inductance in the output circuit of said generator, and a transmission line tapped on the one hand to points on said last named inductance, and on the other hand to one of said parallel inductances.

4. In transmitting apparatus a thermionic generator, an aerial system, and means whereby the amplitude of the energy supplied to said aerial system may be varied without varying the frequency of the oscillations radiated including an aerial capacity connected through parallel inductances to

ground, a capacity in series with one of said parallel inductances, an inductance in the output circuit of said generator, and a transmission line tapped on the one hand to points on said last named inductance, and on the other hand to one of said parallel inductances.

5. Signalling means comprising a thermionic generator, an alternating current load circuit supplied by said generator, said load circuit including an inductance, and means whereby the amplitude of the energy supplied to said load circuit may be varied without varying the frequency of the oscillations impressed on said load circuit comprising a capacity and an inductance conductively connected in parallel to the inductance in said load circuit, an inductance in the output circuit of said generator, and a transmission line tapped on the one hand to said last named inductance and on the other hand to one of said parallel inductances.

6. Signalling means comprising a thermionic generator, an alternating current load circuit supplied by said generator, said load circuit including an inductance, and means whereby the amplitude of the energy supplied to said load circuit may be varied without varying the frequency of the oscillations impressed on said load circuit comprising an inductance conductively connected in parallel to the inductance in said load circuit, an inductance in the output circuit of said generator, and a transmission line tapped on the one hand to points on said last named inductance and on the other hand to the inductance in parallel with the load inductance.
